METHOD FOR FORMING GROOVES IN ABRASIVE WHEELS

Aleck Block, Culver City, Calif.

Application September 20, 1956, Serial No. 610,936

6 Claims. (Cl. 51—281)

This invention relates to a method for forming grooves in abrasive wheels.

It is an object of my invention to provide an improved method for forming grooves in abrasive wheels, particularly those of the type comprising a plurality of leaves having their inner ends secured to a central core, with a groove being formed in each side of the wheel concentric with the core, such groove being adapted to receive a ring, flange or other reinforcing member to prevent separation of the leaves from the core.

It has been found that previous methods of forming such grooves are not completely satisfactory. If a groove is formed in each individual leaf, there is difficulty in aligning the leaves properly to form a smooth and continuous circular groove. If a groove is cut in the side of the wheel after the wheel is formed, it is both expensive and time-consuming, because the abrasive material on the leaves quickly dulls the die or cutting tool and it must be frequently replaced. While burning the groove avoids these difficulties, it is sometimes difficult to completely control the burning in order to obtain precisely the proper depth or width of groove which is desired. This is particularly important if a ring or flange is to assume a precise position within the groove.

It is an object of my invention to provide a method which overcomes all of these difficulties.

In essence, my invention contemplates forming an annular groove in an abrasive wheel by applying to the side of the wheel a cylindrical member having a relatively thin but dull circular open end. The cylindrical member is suitably attached to a source of rotation and caused to rotate at a substantially high speed. When the open end of the cylindrical member is brought into contact with the abrasive leaves of the grinding wheel, it becomes hot, particularly along its outer edge, and simultaneously burns and grinds a groove in the side of the wheel.

Since the edge of the cylindrical member is not sharp, there is nothing which becomes dull or worn or which must be replaced. My method thus provides the advantages of cutting and the advantages of burning, with the disadvantages of neither.

It is accordingly an object of my invention to provide a method for forming grooves in abrasive wheels having the advantages and benefits of the structure and method set forth above. My invention also comprises such other objects, advantages and capabilities as will later more fully appear and which are inherently possessed by my invention.

While I have shown in the accompanying drawings a preferred embodiment of my invention, it should be understood that the same is susceptible of modification and change without departing from the spirit of my invention.

Referring to the drawings:

Fig. 1 is a front elevational view showing the cylindrical member in position above an abrasive grinding wheel, with the wheel shown in section;

2

Fig. 2 is a similar view with the open end of the cylindrical member broken away and shown partly in section within the groove formed in the wheel;

Fig. 3 is a sectional view of an abrasive grinding wheel with a groove formed in each side thereof;

Fig. 4 is a top plan view of a portion of the wheel after formation of the groove;

Fig. 5 is an enlarged plan view of the area surrounding the groove.

10 A preferred embodiment which has been selected to illustrate my invention comprises an abrasive wheel 10 which is formed of a plurality of leaves 11, the inner ends of which are adhered or otherwise secured to a central circular core 12. At least some of the leaves 11 carry suitable abrasive material.

15 In order to form a groove in the side of the wheel 10, I provide a cylindrical member 13, having a shaft 14 which is adapted to be connected to a chuck 15 or other suitable source of comparatively high speed rotation.

20 The cylindrical member 13 is provided with an open end having a circular wall 16, the edge of which is not necessarily sharpened or pointed. The thickness of the wall 16 is substantially the same or somewhat less than that of the groove being formed.

25 The cylindrical member 13 is mounted above the wheel 10, which may be held in place by any suitable holding means such as indicated in dotted lines in Figs. 1 and 2 of the drawings. The cylindrical member 13 is rotated at a comparatively high speed and then brought downwardly until the circular wall 16 contacts the edges of the leaves 11 forming the wheel 10.

30 While the speed of rotation of the cylindrical member 13 may vary within a considerable range, a speed of approximately 3000 surface feet per minute has been found in practice to produce satisfactory results.

35 As the wall 16 engages the leaves 11, it encounters a substantial amount of frictional resistance from the abrasive material carried by the leaves as well as from the materials forming the leaves themselves. This causes 40 the wall 16 to become heated to a sufficiently high temperature so that it partly burns the edges of the leaves 11 in addition to cutting them. The burning is evidenced by smoke which rises from the wheel during the grooving operation and by a searing type of discoloration which is evident around the groove after it has been formed, as indicated in Fig. 5 of the drawings. Due to the rotation of the cylindrical member 13, the portions of the leaves 11 directly adjacent to the groove are slightly curved in the direction of rotation of the cylindrical member 13.

45 Application of the cylindrical member 13 to the wheel 10 is continued until the desired depth of groove 17 has been formed. The depth of the groove 17 may be easily and accurately controlled. The wheel 10 is then turned and another groove 17 formed in the opposite side of the wheel 10.

50 While any suitable materials may be used to form the cylindrical member 13, it has been found that a piece of spring steel produces satisfactory results with the bottom edge of the wall 16 being no thinner than the remainder of the wall 16.

55 I claim:

1. The method of forming a circular groove in the side edge of an abrasive wheel having a plurality of abrasive leaves comprising mounting a cylindrical member for high speed rotation adjacent the side of said wheel, said cylindrical member having an open end with an unsharpened circular edge, rotating said cylindrical member at a speed of approximately 3000 surface feet per minute with respect to said abrasive wheel, applying the open end of said cylindrical member to the side of said wheel so that the frictional engagement between

the abrasive leaves of said wheel and said cylindrical member causes the portion of said cylindrical member adjacent said open end to become heated, and simultaneously burning and cutting a groove in the side of said wheel through the heating and rotation of said cylindrical member.

2. The method of forming a circular groove in the side edge of an abrasive wheel having a plurality of abrasive leaves comprising mounting a cylindrical member for high speed rotation adjacent the side of said wheel, said cylindrical member having an open end with an unsharpened circular edge, rotating said cylindrical member at a high speed with respect to said abrasive wheel, applying the open end of said cylindrical member to the side of said wheel so that the frictional engagement between the abrasive leaves of said wheel and said cylindrical member causes the portion of said cylindrical member adjacent said open end to become heated, and simultaneously burning and cutting a groove in the side of said wheel through the heating and rotation of said cylindrical member.

3. The method of forming a circular groove in the side edge of an abrasive wheel having a plurality of abrasive leaves comprising mounting a cylindrical member for high speed rotation adjacent the side of said wheel, said member having an open end with an unsharpened circular edge, rotating said member at a high speed with respect to said abrasive wheel, applying the open end of said member to the side of said wheel so that the frictional engagement between the abrasive leaves of the said wheel and said member causes the portion of said member adjacent said open end to become heated, and simultaneously burning and cutting a groove in the side of said wheel through the heating and rotation of said member.

4. The method of forming a groove in the side of an abrasive wheel having a plurality of abrasive leaves com-

prising mounting a member for high speed rotation, said member having an open end with an unsharpened edge, rotating said member at a high speed with respect to said abrasive wheel, applying the open end of said member to the side of said wheel so that the frictional engagement between the abrasive leaves of said wheel and said member causes the portion of said member adjacent said open end to become heated, and simultaneously burning and cutting a groove in the side of said wheel through the heating and rotation of said member.

5. The method of forming a groove in the side of an abrasive wheel having a plurality of abrasive leaves comprising rotating a member having an open end with an unsharpened edge at a high speed with respect to said wheel, applying said edge to the side of said wheel, so that the frictional engagement between the abrasive leaves of said wheel and said member causes the edge of said member to become heated, and simultaneously burning and cutting a groove in the edge of said wheel through the heating and rotation of said member.

6. The method of forming a groove in the side of an abrasive wheel having a plurality of abrasive leaves comprising rotating a member having an edge, applying said edge to the side of said wheel so that the frictional engagement between the abrasive leaves of said wheel and said member causes the edge of said member to become heated, and simultaneously burning and cutting a groove in the edge of said wheel through the heating and rotation of said member.
